ELECTROCARDIOGRAM PLATE ELECTRODE

Arthur J. Hinnenkamp, Excelsior, Minn., assignor to
Medical Plastics, Inc., Minnetonka, Minn.

Filed Feb. 22, 1972, Ser. No. 228,430

Term of patent 14 years

Int. Cl. D24—01; D24—99

U.S. Cl. D83—1 F

FIG. 1

FIG. 2

FIG. 3

FIG. 4

FIG. 5

FIG. 6

FIG. 7

FIG. 8

FIG. 1 is a top plan view of the electrocardiogram plate electrode showing my new design;

FIG. 2 is a bottom plan view of the electrode of FIG. 1;

FIG. 3 is a side elevational view of the right side of FIG. 1, the left side being a mirror image;

FIG. 4 is an elevational view of the lower end of FIG. 1, the upper end being a mirror image;

FIG. 5 is a top plan view of a modification of the electrocardiogram plate electrode of my new design;

FIG. 6 is a bottom plan view of the electrode of FIG. 5;

FIG. 7 is a side elevational view of the right side of FIG. 5, the left side being a mirror image; and

FIG. 8 is an elevational view of the lower end of FIG. 5, the upper end being a mirror image.

I claim:

The ornamental design for an electrocardiogram plate electrode, substantially as shown and described.
